STEREOPTICON VIEWER CABINET

Raymond C. Bluem, Minneapolis, Minn., assignor to Toro Manufacturing Corporation of Minnesota, Minneapolis, Minn., a corporation of Minnesota

Application June 7, 1954, Serial No. 30,859

Term of patent 14 years

(Cl. D61—1)

Figure 1 is a side elevational view of a stereopticon viewer cabinet, showing my new design;

Figure 2 is a front elevational view thereof; and

Figure 3 is a top plan view thereof.

The side of the viewer not shown is the same as the side shown and the rear thereof is plain.

I claim:

The ornamental design for a stereopticon viewer cabinet, as shown and described.
